BROODER

James Russell Williams, Quincy, Ill.

Application November 19, 1934, Serial No. 753,727

4 Claims. (Cl. 126—93)

This invention relates to an improvement in brooders.

Heretofore, it has been customary to use a canopy as a part of a brooder in order to deflect 5 the heat downward onto the floor space thereunder sufficiently to keep the chicks warm.

In the ordinary canopy brooder, heat from the heating-drum or chamber radiates somewhat toward the floor, but most of it radiates 10 inside the canopy and is then deflected toward the floor. I have found that only about 60% of the heat radiated under the canopy is deflected downwardly, and the rest is absorbed or radiated upwardly.

15 The object of my invention is to eliminate the canopy usually required, and to effectively heat the floor space sufficiently without the use of a canopy, so that brooding conditions will be very substantially improved.

20 In my improved brooder, the chicks are always accessible and may be readily inspected since they are not confined under a dark, stuffy canopy. The floor of the brooder-house may be effectively cleaned and swept without removing a bulky 25 canopy, such as has been necessary heretofore.

The unit is very effective as a room heater for a brooder-house since the recirculating passageways cover such an area that a tremendous 30 amount of air is warmed continuously, and is recirculated throughout the room, thereby materially improving brooding conditions.

35 This improved brooder is cheaper to manufacture than the same size stove with the ordinary canopy due to the savings of material and labor in the large canopy and in the drum which is ordinarily provided in an oil burning brooder of the enclosed type.

40 In carrying out my invention, I utilize a base which encloses a central heating-chamber, within 45 which is mounted a heater such as an oil-burner of the usual type for heating brooders, and I provide radially arranged circulating passageways which communicate with the heating-chamber and extend outwardly therefrom and then back to the top of the central casing for 50 central discharge. These circulating passageways are arranged relatively close to the floor, normally about ten inches (10'); there is a sufficient 55 number of them, and they are arranged sufficiently close together so as to heat the floor space beneath and between the same to normal brooder temperature without the space being enclosed or covered by a canopy. These radiating passageways are formed in casings of arms which

are shaped to effect a substantial downward radiation of the heat.

The invention is illustrated in the accompanying drawing, in which:

Fig. 1 is a top plan view of my improved 5 brooder;

Fig. 2 is a vertical sectional view therethrough; and

Fig. 3 is a detail transverse sectional view 10 on the line 3—3 of Fig. 2.

In the construction illustrated in the drawing, the brooder comprises a central casing or base 1, which is divided by a partition 2 into a combustion chamber 3 and a top chamber 4, the latter being closed by a top 5 which covers the 15 top of the casing or base 1.

Mounted in any suitable manner within the casing or base 1 is a burner or other heating element designated 6, which, according to the illustration is shown as an oil-burner connected by a 20 pipe 7 to a source of oil supply 8. Connected in the pipe 7 is a thermostatically actuated control device designated generally by the numeral 9, which may be of well-known construction such as is ordinarily used for brooders, and 25 which need not be described in detail herein. In order to support combustion within the casing or base 1, air may be admitted to the burner 6 through screened openings 10 arranged in the 30 lower part of the base.

The casing or base 1 is provided with two series of openings 11 and 12 arranged respectively below and above the partition 2 at opposite ends of circulating passageways 13 which 35 extend radially from the casing or base 1.

Each of the circulating passageways 13 is formed in a structure designated as a radial arm 14, which is constructed of upper and lower sections as shown in Fig. 3, separated by a partition 15, which extends outwardly from the periphery of the casing 1 approximately to the outer end of the arm 14, but leaving an opening around the end of the partition 15 sufficient to permit the heating medium for the combustion chamber to pass from the lower to the upper 45 portions of the circulating passageways 13. The outer end of the arm 14 is closed by an end wall 16.

Thus the circulating passageway 13 communicates at one end with the combustion chamber 3 50 and at the other end with the top chamber 4, so that the heating medium is circulated through the passageway 13 and returns into the chamber 4, from which it is discharged through a pipe 17. In this way, the heat from the burner 6 is 55

circulated out over the area where the chicks are kept, and then back to the flue 17.

The lower section of each arm structure 14 is semi-rounded, as shown in Fig. 3, so that heat will be radiated downward toward the floor and also diagonally from the rounded side walls to effectively heat the space between the adjacent arm structures which enclose the circulating passageways 13, thus affording sufficient heat for the brooder without the necessity of a canopy which offers many disadvantages that have been eliminated by this invention.

The spaced arrangement of the radial arms 14 without a canopy or cover thereover, allows a recirculation of air within the brooder house between the arms. This maintains a fresh air condition in the brooding area, and eliminates foul air by reason of the fact that the air around the chicks is recirculated upwardly between the arms to the upper part of the brooder house, then downwardly and into the brooding area, thus continually changing the air in the brooding area and recirculating the air in the brooder house. This provides better living conditions for the chicks and a more accessible brooding area.

I claim:

1. A brooder comprising a base adapted to rest on a brooder floor and having a plurality of radial structures extending outwardly a substantial distance from said base, each of said structures having a passageway therein, means for supplying a heating medium to the inner ends of said passageways, flue means communicating with the outer ends of said passageways for discharge of said heating medium, said radial structures being spaced apart for recirculation of air therebetween, the lower walls of said radial structures forming downward heat radiating surfaces and being arranged adjacent the lower end of the base to be located relatively close to the floor.

2. A brooder comprising a base adapted to rest on a brooder floor and having a chamber therein with a plurality of radial structures extending outwardly a substantial distance from an upper portion of said chamber, each of said structures having upper and lower passageways therein which communicate at the outer end of the radial structure, means for supplying a heating medium to said chamber, said chamber com-

municating with the inner ends of the lower passageways, and a flue outlet communicating with the inner ends of the upper passageways, said radial structures being spaced apart for recirculation of air therebetween, the lower walls of said radial structures forming downward heat radiating surfaces and being arranged adjacent the lower end of the base to be located relatively close to the floor.

3. A brooder comprising a base having a chamber therein with a plurality of radial arms extending outwardly from an upper portion of said chamber, each of said arms being tubular and having a horizontal partition therein dividing the arm into upper and lower passageways which communicate at the outer end of the arm, means for supplying a heating medium to said chamber, said chamber communicating with the inner ends of the lower passageways, and a flue outlet communicating with the inner ends of the upper passageways, said arms being spaced apart and forming open-ended sector shaped interspaces, the space above and below the arms being unobstructed, thereby permitting ready access to and recirculation of air to and from the space below said arms, the lower walls of said arms forming downward heat radiating surfaces.

4. A brooder comprising a base having a chamber therein with a plurality of radial arms extending outwardly from an upper portion of said chamber, each of said arms being tubular and having a horizontal partition therein dividing the arm into upper and lower passageways which communicate at the outer end of the arm, a burner in said base for supplying a heating medium to said chamber, said chamber communicating with the inner ends of the lower passageways, and a flue outlet communicating with the inner ends of the upper passageways, said arms being spaced apart and forming open-ended sector shaped interspaces, the space above and below the arms being unobstructed, thereby permitting ready access to and recirculation of air to and from the space below said arms, said arms having the outer walls of the lower passageways of greater area than the outer walls of the upper passageways and forming downward heat radiating surfaces.

JAMES RUSSELL WILLIAMS. 50
